UNITED STATES PATENT OFFICE.

MAXON CHASE, OF LUCERNE, MISSOURI.

HAY-RICKER.

SPECIFICATION forming part of Letters Patent No. 475,200, dated May 17, 1892.

Application filed June 26, 1891. Serial No. 397,658. (No model.)

To all whom it may concern:

Be it known that I, MAXON CHASE, of Lucerne, in the county of Putnam and State of Missouri, have invented a new and useful 5 Improvement in Hay-Rickers, of which the following is a specification.

This invention relates generally to an improved hay stacking or ricking device, and more particularly to the improved mechanism 10 for operating the stacking or ricking fork or head, the object of my invention being to provide an automatic mechanism that shall be safe at all times, one that shall dispense with weights, and one that shall consist of a 15 few simply-constructed and assembled parts, requiring a minimum force to operate the same.

With these objects in view my invention consists in the peculiar construction of the 20 several parts and their novel combination or arrangement, all of which will be fully described and claimed hereinafter.

In the drawings forming a part of this specification, Figure 1 is a side view of my 25 device, the stacker-arms being shown elevated in dotted lines. Fig. 2 is a top plan view of the same. Fig. 3 is a rear view. Fig. 4 is a detail plan view showing the spring- 30 actuated locking-pawl, and Fig. 5 is a detail side view of the pawl locking and unlocking mechanism.

In constructing my improved stacker or ricker I employ a base-frame or platform A, an upright frame or truss B, and the diagonal 35 guiding-braces C C, connecting the base and upright frames A and B. Stack-arms D D are pivotally attached to the upright frame near its lower end, and upon the outer or free ends of the said arms is mounted a 40 stacking or ricking fork or head E, of any approved construction. A bearing platform or beam F is attached to the upright frame B near its lower end, and a short distance above said beam is a second beam F', while 45 at the top of the frame is arranged a cross-beam G, said beams being arranged upon the rear side of the frame, and upon the opposite ends of the top cross-beam are mounted the guiding-sheaves or pulleys H H. A rev- 50 oluble vertical shaft K is journaled in the beam F and top cross-beam G, said shaft projecting a short distance above the top cross-

beam, and upon the lower portion of the shaft K a winding-drum L is rigidly mounted. Elevating-ropes M M are attached to the 55 upper end of the shaft K, said ropes extending in opposite directions, being passed through the sheaves or pulleys and attached to the stacker or ricker arms adjacent to the fork or head, the said ropes being adapted to 60 wind upon the shaft when it is revolved, thus elevating the fork or head, and in order to revolve the shaft K an operating-rope N is wound upon the drum and adapted to be drawn by horse or other power to revolve the 65 drum and shaft. The upper face of the winding-drum is provided with a ratchet wheel or disk O, and upon the beam F' is pivoted a spring-actuated pawl P, adapted to engage the ratchet wheel or disk, the outer end of 70 said pawl projecting beyond the end of upright frame, and is made hook-shaped, as shown. This pawl has also a certain amount of vertical movement, the purpose of which will appear farther on. A locking-plate R is 75 attached to the side of the upright frame adjacent to the pawl, said plate being formed with a shoulder r, which engages and locks the pawl at certain periods, and said plate is also provided with a guide-loop r', through 80 which the releasing-bolt R' works, said bolt operating to lift the pawl from the shoulder r and allow it to spring back in engagement with the ratchet wheel or disk. A tripping-arm T is attached to the rear end of the stacker 85 or ricker arm D, adjacent to the bolt, the purpose of the tripping-arm being to throw the releasing-bolt upward to move the pawl out of engagement with the shoulder as soon as the fork or head has reached the ground. 90

In operation the hay is deposited upon the fork or head and the rope on the drum unwound, thereby revolving the shaft winding the elevating-ropes upon the upper portion of shaft and raising the fork or head to an 95 upright position, thereby stacking or ricking the hay. The pawl being in engagement with the ratchet wheel or disk prevents the shaft revolving in the opposite direction, and thus holds the fork or head in whatever position it may be should the rope be slackened. When the fork and arms have been raised to an upright position, the arm adjacent to the hooked end of pawl engages said hooked end,

pushing it back and throwing the pawl out of engagement with the ratchet wheel or disk. The hooked end of the pawl now drops by its own weight a certain distance, and thus engages the shoulder on the plate and is locked out of engagement. The shaft is now free to revolve in the opposite direction and the arms and fork are free to descend, winding the operating-rope upon the winding-drum. When the arms reach a horizontal position, the tripping-arm strikes the releasing-bolt, throwing it up, unlocking the pawl, and the stacker or ricker is again ready for operation.

Having thus described my invention, what I claim as new is—

1. In a stacker or ricker, the combination, with the base and upright frames, arms, and fork or head, of a revolute shaft, the elevating-ropes, operating-rope, the pawl, and automatic locking and unlocking devices, arranged and operated substantially as shown and described.
2. In a stacker, the combination, with the arms and fork, of a revolute vertical shaft, the elevating-ropes, a ratchet-wheel mounted on said shaft, a spring-actuated pawl, a lock-

ing device to hold said pawl, an unlocking bolt, and a tripping-arm for operating said unlocking-bolt, substantially as shown and described.

3. In a stacker, the combination, with the arms and fork, of a revolute shaft, the elevating-ropes, a ratchet-disk, a spring-actuated pawl having a hooked end, a combined locking and guiding plate, a releasing-bolt working in said guide-plate, and a tripping-arm attached to the stacker-arm, substantially as shown and described.

4. In a stacker, the combination, with the arms and fork, of the revolute vertical shaft, the elevating-ropes, the winding-drum, the operating-rope, the ratchet-wheel, spring-actuated pawl having a hooked end, the plate having a locking-shoulder and guiding-loop, the releasing-bolt working in said loop, and the tripping-arm attached to one of the stacker-arms to operate the releasing-bolt, substantially as shown and described.

MAXON CHASE.
